DESK

Warren Platner, 100 Mansfield Road, North Haven, Conn.

Filed Dec. 5, 1963, Ser. No. 77,683

Term of patent 14 years

(Cl. D33—7)

The undisclosed surfaces of the drawer members and the rear surface of the vertical planar wall are all plain and unornamented while the edge of the wall not shown in FIGURE 3 is like the edge shown.

The dominant features of my design reside in the portions shown in full lines.

I claim:

The ornamental design for a desk, substantially as shown
